US0D1022952S

(12) **United States Design Patent** (10) **Patent No.:** **US D1,022,952 S**
(45) **Date of Patent:** **** Apr. 16, 2024**

(54) **HEADPHONES**

(71) Applicant: **Apple Inc.**, Cupertino, CA (US)

(72) Inventors: **Eric Treski**, Manhattan Beach, CA (US); **Christina J. Smiechowski**, West Hollywood, CA (US); **Robert D. Brunner**, Glen Ellen, CA (US); **Christopher Kuh**, San Francisco, CA (US); **Achille Biteur**, San Francisco, CA (US)

(73) Assignee: **Apple Inc.**, Cupertino, CA (US)

(**) Term: **15 Years**

(21) Appl. No.: **29/912,645**

(22) Filed: **Sep. 21, 2023**

Related U.S. Application Data

(63) Continuation of application No. 29/881,972, filed on Jan. 9, 2023, now Pat. No. Des. 999,757, which is a continuation of application No. 29/837,110, filed on May 2, 2022, now Pat. No. Des. 975,051, which is a continuation of application No. 29/802,917, filed on Aug. 9, 2021, now Pat. No. Des. 950,518, which is a continuation of application No. 29/759,871, filed on Nov. 25, 2020, now Pat. No. Des. 927,454, which is a continuation of application No. 29/697,456, filed on Jul. 9, 2019, now Pat. No. Des. 904,338, which is a continuation of application No. 29/615,486, filed on (Continued)

(57) **CLAIM**

The ornamental design for headphones, as shown and described.

DESCRIPTION

FIG. 1 is a top front perspective view of headphones showing the claimed design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the headphones that form no part of the claimed design.

1 Claim, 6 Drawing Sheets
